Renewed July 22, 1939

7 Claims. (Cl. 74—46)

This invention relates to engines of the internal combustion type and particularly to an equilibrated oscillating engine in which the use of cranked driving shafts is dispensed with and the rectilinear motion of balanced pistons translated into oscillatory motion and finally into continued curvilinear motion of a driven shaft in such manner as to secure an equilibrated working action of the working parts without resort to balanced shafts or other essentially required balancing means, and whereby the number of cylinders and pistons required to obtain a balanced working action and to transmit a certain power force may be reduced to a minimum, while allowing power impulses and a power transmitting force to be obtained equal in number and force value to those obtained by the use of a multiplicity of cylinders in engines of conventional types.

One object of the invention is to provide an engine in which the working actions of two, or multiples of two, pistons may be alternately transmitted to an oscillatory power element which in its oscillations will transmit power through intermittently acting motion transmitting devices to a rotary shaft or the like, whereby the shaft may be continuously driven in a single direction.

A further object of the invention is to provide means whereby the number of working impulses of the pistons may be multiplied with respect to the speed of the rotary shaft, as compared with the number of working impulses obtained in engines of conventional types, whereby the number of working impulses transmitted to the shaft on each of its revolutions will be equal to that obtained in conventional engine structures by the use of a materially greater number of cylinders, and whereby a balanced working action will be secured and an engine of simple construction but of high working power produced.

A still further object of the invention is to provide an engine having a novel working cycle of its pistons, whereby the production of an engine of the stated characteristics is made possible.

A still further object of the invention is to provide an engine which while comprising a relatively small number of pistons and other working parts, reducing its weight and cost of construction, maintenance and operation, will deliver power equal to that furnished by conventional types of engines employing a much larger number of pistons.

A still further object of the invention is to provide an engine which dispenses with the use of elements essential to the operation of other internal combustion engines, whereby an engine of greater simplicity is produced.

With these and other objects in view, the invention consists of the features of construction, combination and arrangement of parts, herein-after fully described and claimed, reference being had to the accompanying drawings, in which:

Fig. 1 is a vertical transverse section through the engine taken substantially on line 1—1 of Fig. 2.

Fig. 2 is a vertical front-to-rear section through the engine.

Fig. 3 is a vertical transverse section through the cylinders and cooperating working parts on an enlarged scale.

Fig. 4 is a detail section on line 4—4 of Fig. 3.

Figs. 5, 6, 7, 8, 9 and 10 are vertical transverse sections taken respectively on the lines 5—5, 6—6, 7—7, 8—8, 9—9 and 10—10 of Fig. 2.

Fig. 11 is a sectional plan view of the cylinders and elements of the fuel and air inlet valves.

Fig. 12 is a horizontal section through the fuel tank and fuel charge feed valve.

Figs. 13, 14 and 15 are similar sections through the fuel charge feed valve.

Figs. 16 and 17 are face views of the liner walls of the fuel charge feed valve casing.

Fig. 18 is a view of the fuel feed charge valve.

Referring now more particularly to the drawings, A and A' designate outer and inner casings which may be of any suitable construction, but preferably are of the sectional construction hereinabove more fully described. The inner casing supports a pair of cylinders B, B' in which operate pistons C, C'. The rods D, D' of these pistons are coupled to the telescopic slide members d of diametrically opposed lever arms E, E' of a hollow oscillatory sleeve F movable about a driven shaft G journaled in the casings, said shaft having an outwardly projecting end portion G'. This hollow sleeve is cut away at its top and forms a housing receiving the lower end of an oscillatory yoke G2. This yoke G2 is also movable at its lower end about the shaft G as a center and is provided with a longitudinal slot g receiving a crank pin g' on an eccentric comprising spaced disks G3 fixed for rotation on and with a motion transmitting central shaft H journaled in the inner casing A'. Integral with or suitably fixed to the shaft G for rotation therewith are a small gear f, a large gear f' and an intermediate sized gear f2. The gear f' 55

meshes with a gear pinion h on the shaft H , the gear f with gear h' on a second motion transmitting shaft H' , and the gear $f2$ with an idler gear $h2$ journaled on the casing A' for free rotation about one end of the shaft H . Journaled in the casing A' parallel with shaft H' is a third motion transmitting shaft $H2$ carrying a gear $h3$. Also journaled on the casing A' for free rotation about the end of the shaft H opposite that on which gear h is mounted is an idler gear $h4$ driven by a gear $f3$ fixed to rotate with shaft G . The gears f, h are of 4 to 1 ratio or of other suitable ratio to drive the shaft H at multiplied speed with relation to the speed of shaft G . The shaft G , for example, may have a normal working speed of 1000 R. P. M. so that through the stated ratio of gears f, h the shaft H will be driven at a speed of 4000 R. P. M. This multiplied speed of shaft H with relation to that of shaft G is for the purpose of securing a predetermined high speed action of the pistons C, C' to obtain and apply to the shaft G a large number of power strokes on each of its revolutions, as hereinafter described. At this high speed of the shaft H objectionable friction might tend to occur at the bearing ends of said shaft. The idler gears $h2, h4$ are provided to reduce this friction to a reasonable degree. To this end the gear $h2, h4$ turns in a bearing bushing i on the casing A' and the adjacent end of the shaft H has fixed thereto for rotation therewith a bushing i' which rotates in the hub of the gears $h2$, which is driven through a gear ratio of the gears $f2, h2, h4$ at a suitable intermediate speed between that of the shaft G and that of the shaft H , say at 2000 R. P. M., thus reducing the friction on the bearing i' to such a degree that overheating is not liable to occur. The gear $h4$ also rotates on a bushing $i2$ fixed to the adjacent end of shaft H , which reduces friction at this point, but a single bushing being necessary here because gear $f3$ is intermittently instead of continuously rotated and the gear ratio of gears $f3, h4$ is less than that of gears $f2, h2$. The idlers $h2, h4$ further serve as small fly wheels or balancing elements tending to maintain the continuity of motion of shaft G at its intended normal speed.

On the gear $f3$ is a ratchet toothed clutch face j which engages a ratchet toothed clutch face j' on a drive gear J fixed to oscillate with the oscillatory sleeve F and slidably mounted on said sleeve for movement of its clutch face j' toward and from the clutch face j . A spring $j2$ acting on gear J serves to hold these clutch faces in engagement. The teeth of these clutch faces j, j' extend in the direction of rotation of the shaft G so that on the oscillator stroke in that direction direct motion will be transmitted to the gear J to drive the shaft G from the oscillator, while on the oscillator stroke in the opposite direction the clutch teeth of the clutch face j' will slip idly over the clutch teeth of the clutch face j . The gear J meshes with the gear $h3$ on the shaft $H2$, which in turn meshes with a gear J' loose on shaft H' , which gear J' has a ratchet toothed clutch face $j3$ for engagement with a ratchet toothed clutch face $j4$ fixed to the shaft $H2$. A spring $j5$ acts on the gear J' to hold the clutch faces in engagement in one direction of rotation of the gear J' while permitting the teeth of said clutch faces to slip idly over one another on the reverse direction of rotation of said gear. The gear J' rotates in the reverse direction to the gear J and the clutch teeth of the clutch

faces $j3, j4$ are so arranged with respect to the teeth of the clutch faces of gear $j3, J$ that in the oscillation stroke direction of the oscillator F during which gear J transmits motion to gear $f3$ gear J' driven by gear J through gear $h3$ will turn idly, while on the reverse oscillation stroke of the oscillator F gear J through gear $h3$ will turn gear J' in the direction to rotate shaft H' , the motion of which will be transmitted through gears h' and f to shaft G to turn the shaft G in the same direction as that obtained by the rotation of gear $f3$. Thus on each oscillation stroke of the oscillator motion will be alternately transmitted through the sets of clutch gears to continuously rotate the shaft G in a single direction, the reciprocatory motions of the pistons being converted into oscillatory motion of the oscillator and then through the ratchet clutches into curvilinear or continued rotary motion of shaft G . The ratio of the sets of gears which drive the shaft G from the oscillator is or may be such, as stated, as to drive the shaft G at a normal working speed of 1000 R. P. M. while enabling this speed to be varied within predetermined higher and lower limits by varying the working actions of the piston B, B' in the cylinders C, C' .

It will be observed by the construction above described that the pistons C, C' are adapted to reciprocate on straight lines in their cylinders B, B' and may be fixed to the piston rods, whereby wobbling motions of the pistons in the cylinders causing wear and tear on the piston walls and piston rings such as produced by irregularities of motion in which the rods are coupled to the cranks of a crank and pivotally to the pistons are avoided. Hence a longer life period of usefulness of the cylinders and pistons is ensured and at the same time a perfect seal between the cylinder walls and pistons may be maintained to allow high fluid pressures in the cylinders to be used without liability of leakage and faulty actions. This sealing action is one factor which permits of a novel working cycle of my engine hereinafter described whereby increased power may be obtained, the use of parts heretofore employed eliminated, and an engine of light weight produced because of the elimination of parts and the reduction of the number of cylinders required to furnish driving power as compared with an engine of ordinary type.

As stated, the shaft H and eccentric $G3$ are rotated at multiplied speed with respect to the shaft G . This is for the purpose of controlling the working movements of the pistons to multiply the number of power impulses per revolution applied to the shaft G . The lower end of the yoke $G2$ is provided with oppositely extending wings or abutments $g2$ disposed in the direction of the arms E, E' on opposite sides of the shaft G . Between these abutments $g2$ and a stationary abutment or abutments $g3$ in the oscillator housing sleeve are coiled springs $g4$ forming yielding motion transmitting connections between the respective oscillator arms E, E' and the yoke $G2$. As the shafts G and H rotate the rotation of the shaft H and eccentric $G3$ at four times the speed of the shaft G permits of four complete working cycles of each piston on each rotation of the shaft G and of eight power impulses being applied to said shaft on each revolution thereof. The abutments $g2$ and $g3$ and springs $g4$ not only serve as yielding motion transmitting connections between the yoke $G2$ and oscillator F , but provide stops for elastically limiting the working strokes of the pistons and

the working strokes of the arms E, E' under normal or optimum working conditions while permitting such parts to have extended ranges of motion to meet and automatically compensate for different load changes or working conditions in the cylinders. The springs and abutments further serve to prevent shocks at the ends of the working strokes of the oscillator arms and pistons so that a smooth working action of these parts will be obtained.

The arms E, E' have, in the up and down motions of the pistons, a normal range of motion through an arc of 45°, more or less, in each direction of movement between their normal stroke limits. The elastic connections formed by the abutments g₂, g₃ and springs g₄ between the governing eccentric and oscillator, however, allow the pistons to have an extended range of movement in each stroke direction, that is, either on a power stroke, in the event that the piston is impelled on such stroke by an excessive working charge, or on a compression stroke in the event that a normal compression stroke is not sufficient to compress a deficient charge. This is of importance in securing a highly efficient operation of the engine in utilizing to the fullest extent all the available power which can be developed from the full charges supplied and in effecting auto-ignition of the charges, which this engine is designed to secure, and a novel cycle of action of the engine, whereby the use of ignition mechanism (except for starting) as well as carburetors, vaporizers and other charge forming, conditioning and igniting devices may be dispensed with and the construction of the engine correspondingly simplified and the working power of the engine of any given size and weight enormously increased. This novel cycle of operation also adapts the driven shaft of the engine to work at a comparatively low speed, the engine to operate at any altitude without superchargers or other special means, and the speed of the shaft to be flexibly varied within wide ranges with respect to normal, making the engine especially valuable for aircraft use. The means, in addition to the features already described, for securing this normal working cycle and advantages will now be more fully set forth.

Each cylinder is provided near its lower end with an annular series of exhaust ports k and an annular series of air inlet ports k'. About the cylinder is a jacket K in spaced relation thereto to provide an air space or chamber k₂ communicating at its lower end with the ports k' and at its upper end with an annular air intake compartment k₃ formed by a head k₄ having arcuate air intake ports k₅ formed therein. An oscillatory valve k₆ is mounted on the head k₄ and provided with coacting ports k₇, which valve may be operated in a manner hereinafter described to supply air to the cylinder for charge forming speed controlling and braking actions. At the top of the cylinder is an air outlet passage l controlled by a vertically movable valve l' adapted to close against a seat l₂ at the bottom of the outlet l. This valve has a stem l₃ extending upwardly and outwardly through the passage l within the space bounded by the head k₄, and a spring l₄ is provided about the stem for normally holding the valve closed. The valve also controls the delivery end of a charge feed passage m or m' which opens into the cylinder through its seat. The passages m and m' of the cylinders B, B' lead thereto from a charge valve chamber M located within the base of a fuel

holding chamber or reservoir N, which fuel may be a suitable hydrocarbon or other volatile liquid fuel. Beneath this reservoir N is positioned a compressed air chamber or reservoir N' in communication with the bottom of each cylinder through a passage containing a spring closed check valve n. This reservoir N' is kept charged with air by displacement of air from the lower ends of the cylinders by the pistons at the limit of their down strokes, the air passing through the check valve n which then closes to prevent its back travel and escape. In the valve chamber M is an oscillatory valve M' in the form of a disk having a pair of feed ports p, q at different radial distances from its center for coaction respectively with pairs of fuel inlet passages p', q' located in opposite walls r, r' of the chamber M for registration with the respective ports p, q on reverse oscillation movements of the valve, which passages are in open communication with the fuel reservoir N. In the walls are also formed outlet passages s, t communicating with the respective charge feed passages m, m' leading to the cylinders B, B', each passage s, t being located in one of the casing walls opposite an air passage s', t', one for each passage s, t, leading from the air chamber N', whereby in the oscillation of the valve in one direction a fuel charge for supply to one cylinder will be picked up by the valve and delivered in the reverse direction of oscillation of the valve by an air blast to said cylinder, the arrangement being such that measured fuel charges or charges of predetermined value or amount will be alternately delivered in timed accord to the respective cylinders. The amount of air supplied with these charges is not intended to be sufficient to form an explosive mixture, the air supplied being only sufficient for a force feed and to effect a partial atomization of the liquid fuel, the remainder of the air for maintaining combustion being furnished by the action of the pistons in the cylinders.

The valve M is provided with peripheral teeth u meshing with the teeth of a gear segment u' carried by the oscillating yoke G₂, whereby said valve is actuated in timed accord with the actions of the pistons.

The working cycle in each cylinder is as follows: Assuming that a charge has been supplied and ignited in the cylinder B the piston C therein will be impelled on its downward or working stroke, thus transmitting downward motion to oscillator arm E. The piston, after having received the full impulse of the gases, passes below the exhaust ports k through which the spent gases exhaust. The piston has an extended range of downward movement, however, in which it passes below ports k', through which pure air enters to take the place of the exhaust gases, and on such downward movement the piston compresses and forces the air in the bottom of the cylinder past the check valve n into the compressed air reservoir N', whereby said reservoir is kept charged with air. As the piston on its upstroke passes above the ports k the valve opens to admit a charge of fuel supplied in the manner before described to the cylinder and then quickly closes. This fuel charge mixes with the air entered through ports k' to form a combustible mixture which on the continued upward movement of the piston is compressed to a density of twelve atmospheres or more or to a density to raise the temperature of the mixture to a point to cause auto-ignition of the mixture and another working stroke of the piston. The

cycle of action is then repeated, and as these operations are alternately carried out in the cylinders B, B' it will be seen that a working impulse will be transmitted on each downstroke of 5 each piston and that on the upstroke or inactive stroke of each piston the other piston will be on its downstroke and transmitting a working impulse, whereby power will be continuously applied to the oscillator. As a result of the action 10 of the controlling eccentric, which is rotated at four times the speed of the driven shaft, and which eccentric controls the actions of the pistons, it further will be seen that each piston through the timing means thus provided will be 15 caused to deliver a power stroke on each 90° part of the revolution of the shaft G, so that through the alternating power actions of the piston eight complete power impulses will be transmitted to the shaft G on each of its revolutions, or one on 20 each 45° part of its revolution. By this means a balanced or equilibrated power transmitting action is obtained by the use of two power cylinders and pistons only, enabling the same degree of balanced power drive to be obtained as 25 that requiring the use of a multiplicity of cylinders in engines of the Otto cycle type or other types heretofore in use, and without the necessity of driving the shaft G at an excessively high speed. My improved construction of engine also 30 avoids the necessity of employing carburetors, vapors or other similar devices and ensures the supply of a proper fuel mixture and its ignition at all altitudes and under all climatic conditions without the necessity of using superchargers at 35 high altitudes. My invention further avoids the necessity of using electrical ignition means except of a simple character for starting the engine, as after the engine is once started into action auto-ignition of the charges is effected. Any 40 suitable means may be employed for taking power from the shaft G, if the element to be driven is not directly driven therefrom, and a clutch and transmission of conventional type may be employed in connection therewith if so desired 45 in the use of the engine on automobiles of various kinds.

In starting the engine suitable starting means may be applied to the end G' of shaft G to rotate the same, which motion in the form of oscillatory motion, will be transmitted through the crank g' and yoke G2 to the oscillator G3, which in turn through the action of the oscillator will reciprocate the pistons to initiate the starting action. In this operation the fuel feed mechanism and admission valves will also be actuated to supply fuel charges to the cylinders, which may be ignited by a simple type of electrical igniter. The means for operating the valves l' 50 may be of any preferred type. In the present instance I have shown the use of rocker arms or levers v each having one end thereof arranged to operate a valve l' and its other end arranged to be engaged by cam members v' on a rotary cam disk V, said cam members being properly 55 disposed to operate the valves at proper time periods. The disk is driven by timing gears v2, v3 from one end of a shaft V', which is driven at its opposite end by a gear v4 thereon receiving motion from a gear element v5 on or driven from 60 the eccentric G3.

The valves k6 are normally set for a partial opening of the ports k5, k1, to a degree to supply air in proper amount for admission to the cylinders through the ports k' for the formation of 65 the explosive charges in the cylinders. By ma-

nipulation of the valves k6 the amount of air supplied may be varied to govern the explosive forces of the charges to flexibly control the speed of the engine within given ranges. The valves k6 also provide a means whereby air in 5 large volume may be supplied to the cylinders to slow down the engine to any desired degree and to cause the engine to serve as a brake for controlling the speed of a vehicle on which the engine is used as a driving agent. To perform 10 such retarding and braking functions the valves k6 are opened more or less widely to supply an increased volume of air to the cylinders. The extent to which the valves k6 are opened governs the action of the engine to different degrees. If 15 the valves k6 are opened to a certain extent beyond the normal the additional air taken in will simply weaken the charges and cause a slowing down of the engine. If the valves k6 are opened to an increased extent the volume of air taken 20 into the cylinder will render nil an explosive action and as the piston will be working against a large volume of trapped air with the result that a braking action will be produced. To restore normal conditions it is simply necessary to return 25 the valves k6 to their normal positions and upon the opening of the valve l' by the actuating cam V the excess air will exhaust through the ports l so that normal working conditions will be restored in the cylinders. If, however, the valves 30 k6 are kept wide open for a braking action the continually renewed trapped air on the opening of a valve l' will blow the admitted charge out through the port l and force the valve l' closed, which action will continue each time the valve l' 35 is mechanically opened as long as the valve k6 is wide open and until said valve k6 is returned to normal position. By this means the speed of the engine may be governed independent of the fuel action and a braking action instituted 40 whenever desired to quickly slow down the engine and to retard the speed or stop the motion of a vehicle on which the engine is used as a propelling agent. Any suitable means for adjusting the valves k6 may be employed. As shown in 45 the present instance, the valve members k6 are provided with gear teeth and connected by gear sets w with a control shaft W in gear, as at w', with an operating shaft W' which may be provided with a hand wheel (not shown) or other 50 means for turning it, whereby the valves k6 may be simultaneously adjusted to like degrees.

It will be understood, of course, that the air traversing the chamber k2 will absorb heat from the cylinder walls, thus aiding in keeping the 55 motor cool and placing the air in a heated condition for effective admixture with the fuel to form the explosive charges. Also it will be seen that the air drawn into the cylinder through the ports k and k' on the upstroke of the piston and impelled largely through said ports on the working stroke of the piston will further cool the cylinder and piston, so that the use of auxiliary cooling devices adding weight and cost may be dispensed with.

The exhaust gasses discharged through the port k may vent to the atmosphere through suitable exhaust passages in the casing sections.

The working parts of the engine may be lubricated in any suitable manner. In the present instance I have shown merely a preferred means for automatically lubricating the cylinders and pistons, as conventional means may be used to lubricate the other working parts. This means for lubricating the cylinders and pistons comprises 70 75

an oil reservoir x which may be formed by or disposed within the base of the engine casing, into which depends from each cylinder an oil feed tube y having at its lower end oil inlets y' , each tube being connected at its upper end through a check valve $y2$ with the lower end of its cylinder, so that on the upward movement of the piston in the cylinder oil will be drawn by suction into the cylinder and distributed by the piston to lubricate the piston and cylinder walls. If desired, this oil so taken up may be distributed by pressure of the pistons to the other working parts of the engine.

The casings A and A' may be of any approved construction, but, as stated, are preferably of sectional construction, this to allow ready assembly, disassembly, cleaning and repair of parts. As shown in the present instance, each casing is made of a top section and a bottom section divided along a line coincident with the line of the cylinder ports k , and each section is also preferably divided along a central vertical line into two sections. The sections of the inner casing A' may be united together and to the outer casing by interlocking or interfitting connections or by fastening means, as preferred, while the sections of the outer casing are preferably united by detachable fastening means. Such fastening means, as shown, comprises grooved ribs z formed on the meeting edges of the divisions of the sections of the casing with which are engaged sliding locking bars z' having ribs to engage said grooves, said bars being movable upwardly and downwardly, respectively, to connect and disconnect the casing sections.

From the foregoing description, taken in connection with the drawings, the construction and operation of my improved type of engine will be readily understood without a further and extended description, and it will be seen that the invention provides an engine having a novel cycle of operation, one which provides for the supply of fuel charges to the engine cylinders without the use of carburetors, vaporizers or like devices, one which provides for auto-ignition of the charges, thereby enabling the use of an ignition mechanism to be dispensed with, except one of simple character for starting purposes, one in which the pistons move in a straight line, thus avoiding piston slap and uneven wear and undue wear and tear on the cylinders and pistons, and at the same time enabling a tight seal between the cylinders and pistons to be obtained to prevent leakages and to enable the novel functions described to be performed, one in which the pistons are permitted to have extended ranges of motion to fully compress efficient charges and to increase their delivered power under excessive charges, one in which the number of reciprocations of the pistons to each revolution of the driven shaft is multiplied, giving a greater number of working impulses to the shaft on each of its revolutions, one in which an equilibrated power transmitting action is obtained without the use of specially constructed balancing means, and one which adapts the working action of the pistons to be regulated to vary the speed of the engine without variance of fuel supply and to enable the engine to be employed for braking purposes. By this means the use of transmission mechanisms and the like may be dispensed with and an engine provided which is of much simpler construction than a conventional type of engine and which will operate with great efficiency at all altitudes. It will be understood, of course,

that the structure disclosed for purposes of exemplification may be modified in various respects within the scope of the appended claims, without departing from the spirit or sacrificing any of the advantages of the invention.

While, for example, a preferred construction designed to effect auto-ignition of the fuel charges is disclosed so that the use of ignition mechanism for such purpose is dispensed with, it is to be understood that the construction may be such as to admit of the use of a conventional or special type of ignition mechanism if desired.

What I claim is:

1. In an engine, a prime mover, a primary oscillator actuated thereby, a driven shaft, means actuated by the primary oscillator for rotating the driven shaft, a second oscillator for imparting oscillatory motion to the primary oscillator, and means including a rotary element driven by the driven shaft at a greater speed than said shaft for oscillating the second oscillator.

2. In an engine, a reciprocatory prime mover, a primary oscillator oscillated thereby, a driven shaft, gearing actuated by said primary oscillator for rotating the driven shaft, said gearing operating to translate the oscillatory motion of the primary oscillator into continuous rotary motion of the driven shaft, a second oscillator for imparting oscillatory motion to the primary oscillator, said oscillators being mounted for oscillatory movements in concentric relation, and gearing between the driven shaft and the second oscillator and including a rotary element driven at a greater speed than the driven shaft for oscillating said second oscillator.

3. In an engine, a reciprocatory prime mover, a primary oscillator oscillated thereby, a driven shaft, gearing actuated by the primary oscillator for rotating the driven shaft, said gearing operating to translate the oscillatory motion of the primary oscillator into continuous rotary motion of the driven shaft, a second oscillator for imparting oscillatory motion to the primary oscillator, gearing between the driven shaft and second oscillator for oscillating the latter, said gearing including a rotary element rotated thereby at a greater speed than the speed of the driven shaft, and elastic motion transmitting and cushioning members between said oscillators.

4. In an engine, a reciprocatory prime mover, a primary oscillator oscillated thereby, a driven shaft, gearing actuated by the primary oscillator for rotating the driven shaft, said gearing operating to translate the oscillatory motion of the primary oscillator into continuous rotary motion of the driven shaft, a second oscillator for imparting oscillatory motion to the primary oscillator, a rotary crank for transmitting oscillatory motion to said second oscillator, and gearing driven by the driven shaft for rotating said rotary crank at a greater speed than the driven shaft.

5. In an engine, a reciprocatory prime mover, a primary oscillator oscillated thereby, a driven shaft, gearing actuated by the primary oscillator for rotating the driven shaft, said gearing operating to translate the oscillatory motion of the primary oscillator into continuous rotary motion of the driven shaft, a second oscillator for imparting oscillatory motion to the primary oscillator, said second oscillator having a slotted yoke arm extending therefrom, a rotary crank engaging said yoke arm for transmitting oscillatory motion to said second oscillator, and gearing actuated by the driven shaft for driving said rotary

crank at a speed which is a multiple of the speed of the driven shaft.

6. In an engine, a reciprocating prime mover, a primary oscillator oscillated thereby, a driven shaft, gearing actuated by the primary oscillator for rotating the driven shaft, said gearing operating to translate the oscillatory motion of the primary oscillator into continuous rotary motion of the driven shaft, a second oscillator for imparting oscillatory motion to the primary oscillator, said second oscillator having a slotted yoke arm extending therefrom, elastic motion transmitting and cushioning connections between said oscillators, a rotary crank engaging said slotted yoke arm for transmitting oscillatory motion to the second oscillator, and gearing for driving said rotary crank from the driven shaft at a speed which is a multiple of the speed of the driven shaft.

7. In an engine, the combination of a pair of motor cylinders, reciprocatory pistons operating therein and movable simultaneously in opposite directions, a rotary driven shaft, a primary oscillator actuated by the pistons, motion transmitting mechanism between the primary oscillator and shaft for translating the reciprocating motions of the pistons into rotary motion of the shaft, a second oscillator mounted concentric with the primary oscillator for transmitting oscillatory motion thereto, elastic motion transmitting and cushioning means between said oscillators, and a rotary crank or eccentric driven by the driven shaft at a speed which is a multiple of the speed of said shaft and operatively coupled to the second oscillator for transmitting oscillatory motion thereto. 5 10 15

MANUEL HUMBERTO
PEREZ SOLOGAISTOA.
